PLATFORM SCALE

William B. Winterbottom, Palatine, Ill., assignor to Borg-Erickson Corporation, Chicago, Ill., a corporation of Illinois

Filed Feb. 27, 1961, Ser. No. 64,130

Term of patent 14 years

(Cl. D52—10)

FIG.1

I claim:

The ornamental design for a platform scale, substantially as shown.
